**POWER TAKE-OFF DEVICE, PARTICULARLY
FOR TIMEPIECES**

George G. Ensign and Glenn T. Soper, Elgin, Ill., and Ossian Lundahl, Orlando, Fla., assignors to Elgin National Watch Company, Elgin, Ill., a corporation of Illinois

Application August 4, 1953, Serial No. 372,292

17 Claims. (Cl. 74—88)

This invention relates to energy-transfer or power take-off structures for transmitting intermittently the effects of an oscillating movement to an element having a unidirectional or integrating motion, and is particularly of value in watches and the like where small amounts of energy are taken from an oscillating balance and caused to move the train.

A feature of the invention is the provision of an oscillating element, a transfer means having projections engaged and directly moved during a part of each stroke of an oscillation of said element, and a detent and stop system which cooperate by limited movement to permit advancement of the transfer wheel during a forward stroke and which detent cooperates with the transfer means during the return stroke by a tangential yielding to permit return of the transfer means for passing of the oscillating element and thereafter serves by resilient tangential return to restore the transfer means to position for a new advancing engagement during the following stroke.

Another feature is the provision of an oscillating element, a transfer wheel having teeth directly engaged and directly moved during a part of each stroke of an oscillation of said element, and a detent member effective upon the transfer wheel to procure tooth-by-tooth forward movements thereof and also effective by tangential motions to permit resiliently-opposed return movements thereof and thereafter to restore the transfer wheel to an engagement-receiving position.

A further feature is the provision of a watch mechanism including a balance and hairspring assembly, a train, a transfer wheel connected for moving the train, an element oscillated with the said assembly and engaging the transfer wheel during the forward and return strokes, and a resilient element moved by the transfer wheel to permit step-by-step advancement of the transfer wheel during the forward strokes of the oscillation cycles and effective by tangential motions to permit retrograde movement of the transfer wheel with subsequent induced restoration thereof during the return strokes of the cycles.

A further feature is the provision of a mechanism including an oscillating element, a transfer wheel directly engaged and moved back and forth by the element, and a member acting upon the transfer wheel to permit a limited and resiliently opposed return movement with automatic restoration thereafter and to permit step-by-step advancements thereof with limitation upon the maximum advancing per cycle.

A further feature is the provision of a mechanism including an oscillating element, a toothed transfer member directly engaged and moved back and forth by said element, and a resilient movement limiting member cooperative with the transfer member to permit the same to move one of its teeth past the said limiting member during forward stroke and to permit retrograde movement of the transfer member during return stroke by a tangential resilient yielding while preventing the return of

the tooth past the said limiting member and effective after the oscillating element has escaped from the transfer member during such return stroke to restore the transfer member to a position ready to receive the oscillating member in the next forward stroke thereof, said limiting member being effective to prevent the transfer member from occupying a position while free of the oscillating element in which the transfer member is not ready for cooperation with the said oscillating element.

10 A further feature is the provision of a mechanism including an oscillating element, a transfer wheel acted upon by the said element to be moved back and forth thereby, and a member acting upon the transfer wheel and having a resiliently opposed tangential movement 15 during the return movement of the transfer wheel and a pawl action during the forward movement of the transfer wheel, said transfer wheel being permitted to move through arcs determined by tooth engagements with said member wherewith the said member is effective to prevent the transfer wheel from remaining at rest in any position wherein it is not ready for engagement by said element.

With these and other features as objects in view, illustrative forms of practice are shown on the accompanying drawings, in which:

25 Fig. 1 is a plan view of a watch assembly including an electrically actuated balance, a train, and a power transfer therebetween in accordance with this invention;

Fig. 2 is an upright section, at a larger scale and substantially on broken lines 2—2 of Figs. 1 and 3, showing transfer parts;

Fig. 3 is a plan view of the cooperative parts, substantially on broken line 3—3 of Fig. 2, with other parts partly broken away and partly omitted for clearness;

30 Fig. 4 is an upright section substantially on line 4—4 of Fig. 3;

Fig. 5 is a diagram corresponding to a part of Fig. 3 but with the parts in another moved position;

Fig. 6 is a similar diagram, with the parts in a third position;

40 Fig. 7 is a plan view as in Fig. 3, of another form of construction;

Figs. 8 and 9 are diagrams of certain parts as in Fig. 7, showing positional limits of movements.

45 As shown in Figs. 1 to 6, a watch assembly has a pillar plate PP with associated bridges and balance cock BC for supporting the various staffs and parts of a train and the balance staff BS having a balance wheel rim BW, a collet HSC connected to a hairspring HS which at its other end is engaged with the hairspring stud HSD, a collet RC having thereon a contact fin 50 and a so-called jewel or roller pin 51. The dial D is conventionally shown. The contact fin 50 engages and moves a contact blade CB near the neutral axis of an oscillation stroke, thereby producing contact of blade CB with a side contact 60 during each cycle: the blade CB and contact 60 are connected by the conventionally shown conductors with a coil C and a battery B so that an electrical impulse flows during each cycle to energize the coil C and thereby produce a magnetically induced action upon the balance wheel BW for maintaining the same in oscillation.

50 During the forward stroke of the balance system, the pin 51 encounters the star wheel SW, shown with eleven teeth or points, but it will be understood that any suitable number may be employed. The star wheel pinion 87 has a like number of points, so that for each movement of the star wheel by the roller pin 51, the wheel 106 meshing with the star wheel pinion 87 is advanced by one tooth.

55 70 A spring 92 has a bent end 92a for engagement with the successive star wheel points and is supported by a rotatable stud 90 mounted with tight friction in the pillar plate

PP. A rotatable block 91 is mounted by its eccentric pivot 91a likewise with tight friction in the pillar plate PP, and serves to limit the movement of the spring end 92a upward in Figs. 3, 5 and 6. The block 91 has a kerf 91k for a screwdriver and, by rotating it, the position of engagement of the spring end with the star wheel points may be varied and therewith the positioning of the star wheel points along the path of the roller pin 51 while the points are at rest (e. g. as in Fig. 3) with a point SW-r ready to receive the roller pin 51 for advancement thereby. Rotation of the stud 90 by engagement of its kerf 90k permits establishing a desired preliminary tension in the spring arm 92 as it rests against the block 91.

In operation, as the balance wheel oscillates, its staff BS carries the roller collet RC through like angles. Assuming that the balance is in its clockwise stroke, as indicated by the arrow in Fig. 3, the roller pin 51 encounters the star wheel point SW-r near the neutral axis, substantially at the time that the fin 50 moves the contact blade CB into engagement with the fixed contact 60 and closes the circuit energizing the motor coil C. The star wheel SW is thereupon moved in a counterclockwise direction from the position of Fig. 3 toward that of Fig. 5, at which the non-concentric arcuate paths of the roller pin 51 and of the star wheel points cause the roller pin to escape from the star wheel point SW-r: immediately prior to this escape, another star wheel point SW-p has engaged and pressed the spring end 92a outward to the dotted line position of Fig. 5, and after passing the spring end has permitted the spring end to return to the full line position. It will be noted that the star wheel SW can move beyond the position shown, by momentum, but its forward movement is restricted by the possible encounter of a next-succeeding point SW-q against the spring end 92a, as indicated by dash lines in Fig. 5, therewith the star wheel point SW-s then overlying the roller collect RC may occupy any position in the rest zone between the full line and dash line positions shown but is prevented from entering the free zone between the dotted line position SW-s and the full position shown for the point SW-r which has just been advanced.

After escaping the point SW-r, the roller pin 51 is carried to the end of the clockwise stroke of the balance system, and then returns in its counterclockwise stroke. The roller pin 51 passes the point SW-r, and encounters the point SW-s and acts upon it to cause a retrograde or clockwise movement of the star wheel SW until escaping therefrom as shown by the full line position in Fig. 6. The retrograde movement of the star wheel SW causes the tooth SW-p which has just passed the spring end 92a to be moved against this spring end and to cause the spring portion 92 to flex from the dotted line to the full line position of Fig. 6. When the roller pin 51 escapes from the point SW-s, the energy stored in the flexed spring 92 now causes the spring to return, into the dotted line position of Fig. 6, until the spring is stopped by the block 90, therewith pushing the point SW-p and the star wheel ahead of it, possibly projecting it farther but again with limitation to the rest zone of Fig. 5 upon engagement of the succeeding point SW-q with the spring end 92a as shown by dash lines in Fig. 6.

Thus the star wheel SW is caused to make a forward movement by the roller pin 51, followed by a retrograde passing movement by the roller pin 51, and finally a forward movement by spring action, for each cycle of balance action and therewith producing a net forward motion of wheel 106 by one tooth.

In practice, the train load upon the wheel 106 acts to limit the free forward movement of the star wheel after the roller pin 51 escapes the star wheel point, while a greater free forward movement occurs as the spring 92 acts until stopped by the block 91. Hence, the stroboscopic effect is that of the points occupying two successive positions. The back-lash or play in the train has been

found sufficient in practice to prevent any apparent retrograde movement of the second hand during retrograde movement of the star wheel, so that a 300 beat system has the appearance of a 300 beat continuously forward movement of the second hand, in lieu of the 150 beat effect presented when the total forward train movement is produced by the roller pin 51 during a single, e. g. clockwise stroke.

In the modified form shown in Figs. 7, 8 and 9, the roller collet RC carries the contact fin 50 as before, and a pin 51 formed as a cylinder of semi-circular section, the diametrical plane face thereof being radial to the axis of the star wheel SW-a when the pin 51 engages a star point (full line, Fig. 9) at the rearward limit of permissible rest position for the star wheel.

The star wheel SW-a is illustrated as having eleven equi-spaced teeth each having an edge 40 for engagement by the pin 51 during the advancement and an edge 41 for such engagement during the return stroke and passing action. These teeth are illustrated as thin, with the edges 40 straight and radial, and the edges 41 straight and nearly radial: thus the bottoms 42 at the tooth gaps are longer than with the form in Figs. 1-6.

The detent spring in Fig. 7 has an end portion 192 mounted in a chordal groove of the frictionally tight adjustment stud 190 having the kerf 191. From the portion 192 extends a portion 192a which is essentially at right angles when the parts are free of stress, and from the portion 192a extends a portion 192b which is free of the star wheel points. At the end of portion 192b, the detent spring has a bight 192c curving through about 170 degrees and joining the portion 192d which lies in the plane of the star wheel for engagement by the points thereof. At the free end, the detent spring has an angularly directed portion 192e also cooperative with the points.

An adjustment block 194 projects from the frictionally fitting stud 194a having a kerf 194b. This block 194 provides an adjustable stop for the detent spring and limits the movement thereof during the advancing of the star wheel SW-a, but leaves the detent spring essentially free to move during return movements of the star wheel.

In operation of the device of Fig. 7, as the balance oscillates, during the forward or clockwise stroke as shown by the arrow (Fig. 8), the pin 51 encounters a star wheel point and causes the star wheel to turn counterclockwise, and escapes therefrom when the pin and star wheel are for example in the position shown in dotted lines in Fig. 9. The star wheel acts at another of its points by pressing outward upon the portion 192d, therewith flexing (Fig. 8) the detent spring at the bight 192c and in the portions 192d, 192b, with insignificant change in the portion 192a, it being noted that the block 194 stops any bodily movement of the portion 192a. Near the end of the engagement of pin 51 with the star wheel point which is being driven, the point acting on the detent spring passes the junction of portions 192d, 192e, i. e. it goes past the position shown in Fig. 8, and the portion 192e of the detent spring acts to accelerate the star wheel, which draws away from the pin 51, so that the power transfer from the pin 51 to the star wheel is confined to the time while a star wheel point is pressing the detent spring outward, i. e. for a limited arc closely at the neutral axis of balance oscillation.

When the portion 192e accelerates the star wheel, it may impart a momentum effect which causes the star wheel to pass beyond the dotted line position of Fig. 9; and in particular the star wheel may have its points occupy any position within a large range, e. g. the point SW-q may lie in any position in the range indicated by the radial lines A and B in Fig. 7.

The forward motion of the star wheel is repeated by the pinion 87, and thus delivered to the train.

During the return or counterclockwise stroke of balance oscillation, Fig. 9, the pin 51 passes the star point

which has just been driven, noting the range of positions possible to the star wheel as shown in Fig. 7. The pin 51 strikes the edge 41 of the next succeeding point, and causes the star wheel to turn backward or clockwise: when the star wheel attains a position as shown by full lines in Fig. 9, the pin 51 escapes and the balance then completes its return stroke. The retrograde movement of the star wheel causes a point to engage the portions 192e of the detent, with a composite effect (Fig. 9) by which the portion 192a flexes and leaves the block 194, and also there is a minor outward movement of portions 192d and 192e; the portion 192d is presented initially to the point during the forward stroke at an angle of about 30° relative to the tangent line, whereas during the return stroke, the portion 192e is presented initially at an angle of 45°, and hence there is a greater component of forces in the directions radial to the star wheel axis during the retrograde movement, and the detent spring also acts through a longer length, so that the spring tends to have its free end portions move bodily rather than to flex.

When the pin 51 escapes the star wheel point during the return stroke, the detent spring acts resiliently to cause the portion 192e to move the star wheel clockwise again until it comes to rest in a position within the range A—B shown in Fig. 7, with a net forward movement by one tooth during the cycle.

In practice, as before, the train can have a backlash from the hands, amounting a permissive movement of 9° at the pinion 87, relative to the first wheel 106 of the train: and this corresponds to the 9° of retrograde star wheel movement during the passing action of the pin 51 during its return.

It will be noted that the form of Figs. 7 to 9 has the positions of the detent spring presented at different angles to the tangent, relative to the transfer wheel SW, the angle of the retrograde-limiting portion 192e being steeper relative to a radius from the transfer wheel axis than the angle of the portion 192d. Hence the effort required for pressing the portion 192d outward for the forward stepping movement is low, while the spring responds to retrograde movement with its relatively tangential yielding during normal retrograde arcuate movement of the wheel SW as produced by the pin 51. In this form, however, the system is protective in event of excessive movement of the wheel SW from any cause: for example, if the train is turned by a resetting device, to move the wheel SW counterclockwise, the detent yields as usual for each point, while for clockwise movement of the wheel SW, the detent yields as during retrograde movement induced from the jewel pin and can go beyond this position and permit the points to pass in succession, in each case without damage to the detent.

It will be understood that the invention is not limited to the illustrative forms of practice, but may be employed in other ways within the scope of the appended claims.

We claim:

1. A power take-off structure for an oscillating device and effecting intermittent net forward motion of a driven element, comprising transfer means in driving relation to said driven element and having projections, a part oscillated by said device and effective to engage and move projections of said transfer means during the forward and backward strokes and thereby move said transfer means back and forth, and a resilient detent member cooperative with projections of said transfer means and supported for radial movement relative to the transfer means upon forward motion of the transfer means whereby to permit element-advancing passage of a projection and for limited resiliently opposed tangential movement relative to the transfer means upon backward motion of said transfer means whereby to prevent retrograde passage of a projection.

2. A power take-off structure for an oscillating device and effecting intermittent net forward motion of a driven

element, comprising transfer means in driving relation to said driven element and having projections, a part oscillated by said device and effective to engage and move projections on said transfer means during the forward and backward strokes and thereby move said transfer means back and forth, a resilient detent member cooperative with projections on said transfer means and supported for movement in one direction upon forward motion of the transfer means whereby to permit element-advancing passage of a projection and for limited resiliently opposed movement in another direction upon backward motion of said transfer means whereby to prevent retrograde passage of a projection.

3. A power take-off structure for an oscillating device and effecting intermittent net forward motion of a driven element, comprising a part oscillated by said device, transfer means engaged and moved forward and backward by said part during the forward and return strokes thereof and in driving relation to said driven element, a resilient detent member supported for radial and tangential movement of a portion thereof relative to the transfer means successively by the transfer means whereby radial movement is imparted thereto by the transfer means during forward movement thereof and tangential movement is imparted thereto by the transfer means during return movement thereof, said tangential movement being effective for resiliently opposing such return movement, and a stop limiting tangential movement of said member during the forward stroke of said device.

4. A power take-off structure for an oscillating device and effecting intermittent net forward motion of a driven element, comprising a part oscillating with said device, a transfer wheel having teeth engaged and moved by said part during the forward and return strokes, resilient detent member having two connected angularly-directed legs, the end of one of said legs being supported and the end of the other of said legs being located for engagement by the teeth of the transfer wheel whereby the latter said end can move radially and tangentially relative to the wheel, and a stop for restricting the tangential movement in one direction.

5. A power take-off structure for an oscillating device and effecting net forward motion of a driven element, comprising a transfer means in driving relation to said driven element, a part oscillated by said device and effective to move said transfer means back and forth in time with its own oscillation, and a detent member effective upon the transfer means for permitting successive advancing movement of the transfer means in one direction and effective thereon for limiting return movement thereof in the other direction and effective to impose a restoring movement in said one direction following a said return movement.

6. A power take-off structure for an oscillating device and effective to procure intermittent net forward motion of a driven element, comprising transfer means oscillated by said device and in driving relation to said element, and a detent member cooperative with the transfer means and yielding relative to the transfer means in one direction of movement of said means for permitting element-advancing motion thereof during a forward stroke and yielding in another direction with the transfer means during a retrograde stroke thereof and thereafter returning with said transfer means in the said element-advancing direction of movement.

7. A power take-off structure for an oscillating device and effective to procure intermittent net forward motion of a driven element, comprising transfer means oscillated by said device and in driving relation to said element, and a detent member cooperative with the transfer means and yielding radially relative to the transfer means for permitting element-advancing motion thereof during a forward stroke and yielding tangentially relative to the transfer means during a retrograde stroke

thereof and thereafter returning tangentially in the said element-advancing direction of movement.

8. A power take-off structure for a mechanism having an oscillating device and effective to procure intermittent net forward motion of a driven element, comprising transfer means oscillated by said device and in driving relation to said element, and a detent member cooperative with the transfer means and yielding relative to the transfer means in one direction of movement of said means for permitting element-advancing motion thereof during a forward stroke and yielding in another direction with the transfer means during a retrograde stroke thereof and thereafter returning from said other direction in the said element-advancing direction of movement, said detent member presenting surfaces for initial engagement by said transfer means, said surfaces being angularly disposed relative to one another and a different respective angles relative to a line radial to the axis of the transfer means whereby upon excess retrograde movement of said transfer means the latter can repass said detent member in the reverse direction.

9. A power take-off structure for a mechanism having an oscillating device and effective to procure intermittent net forward motion of a driven element, comprising transfer means oscillated by said device and in driving relation to said element, and a detent member cooperative with the transfer means and yielding radially relative to the transfer means for permitting element-advancing motion thereof during a forward stroke and yielding tangentially relative to the transfer means during a retrograde stroke thereof and thereafter returning tangentially in the said element-advancing direction of movement, said detent member presenting surfaces for initial engagement by said transfer means, said surfaces being angularly disposed relative to one another and at different respective angles relative to a line radial to the axis of the transfer means whereby upon excess retrograde movement of said transfer means the latter can repass said detent member in the reverse direction.

10. A power take-off structure for an oscillatory element and effective for moving a rotary element, comprising a part oscillated by said oscillatory element, a toothed transfer wheel engaged and moved back and forth by said part and connected for driving said rotary element, a detent member supported for radial and tangential movement of a portion thereof relative to the transfer wheel successively by the wheel teeth, and a stop limiting tangential movement of said detent member during one stroke of said part.

11. A structure as in claim 10, in which the member is a blade spring having two angularly directed leg portions, one portion having its end supported and the other portion being presented for engagement by the transfer wheel teeth, and said stop engages the blade spring at the bight between said portions.

12. A structure as in claim 10, in which the member is a blade spring having successive angularly directed leg portions, one portion having its end supported, and two other adjacent portions presenting their bight for engagement by the transfer wheel teeth, the one of said other portions which is engaged by a wheel tooth during retrograde movement having a greater angle to the wheel radius which extends to said bight than the other of said other portions.

13. A power take-off structure for an oscillating device for net forward advancement of a driven element, comprising a part moved forth and back during the strokes of the device, a transfer member included in said driven element, said part being effective to move the said transfer member in a forward direction during its own forward stroke and to move the same in a rearward direction during its own rearward stroke, a detent member engageable by the transfer member and resiliently supported for movements in different directions at angles to one another wherewith during the forward strokes

5 said transfer member causes resilient yieldings and returns of the detent member in one of said directions so that parts of the transfer member successively pass the detent member and produce forward advancements of said driven element, and during the rearward strokes said transfer member causes resilient yieldings and returns of the detent member in another said direction in controlling relation to the transfer member and without retrograde movement of the transfer member past the detent member, and a stop for limiting the return of the detent member following a movement in said other direction.

14. A power take-off structure for an oscillating device and effecting an intermittent forward and backward movement with a net forward advancement of a driven element, comprising a part oscillating with said device, a transfer toothed member included in the driven element, the teeth of which member are in the path of said part and moved in one direction during the forward stroke of said device and moved in the opposite direction during the rearward stroke thereof, a resilient detent member supported for movement of a portion thereof successively by the teeth in two different directions at an angle one with respect to the other, wherewith during the forward strokes the movements of the teeth of said toothed member cause yieldings of said portion in one direction and the teeth successively pass the same with forward advancement of said driven element, and during the rearward strokes the movements of said teeth of said toothed member cause yieldings of said portion in another direction without retrograde passings of the teeth, and a stop for limiting the last mentioned movement of said resilient detent portion during the forward strokes of said device.

15. A power take-off structure for an oscillating device and effecting an intermittent forward and backward movement with a net forward advancement of a driven element, comprising a part oscillating with said device, a transfer wheel included in the driven element and having teeth in the path of said part and moved in one direction during the forward stroke of said device and moved in the opposite direction during the rearward stroke thereof, a resilient detent member supported for radial and tangential movement of a portion thereof relative to the transfer wheel successively by the wheel teeth, wherewith during the forward strokes the movements of the teeth of said wheel cause radial yieldings of said portion and the teeth successively pass the same with forward advancement of said driven element, and during the rearward strokes the movements of the teeth of said wheel cause tangential yieldings of said portion without retrograde passings by the teeth, and a stop for limiting tangential movement of said portion during the forward strokes of said device.

16. A power take-off structure for an oscillating device and effecting intermittent net forward motion of a driven element, comprising a part oscillating with the said device, a transfer wheel having teeth and positioned for cooperation with said part whereby to be moved back and forth by said part during the forward and return strokes of said device, a resilient detent member supported for radial and tangential movement relative to the transfer wheel of a portion contacted and moved successively by the wheel teeth and positioned relative to the path of said teeth so that said wheel has limited freedom of position while at rest but is limited in its free movements by said detent member whereby in any rest position of the wheel there are two teeth thereof presented in the path of movement of said part, said part being effective during the forward stroke to cause a tooth of the transfer wheel to produce a radial movement of a contacted part of said detent member whereby the transfer wheel advances forwardly past the detent member, and a stop for limiting tangential movement of said detent member during such forward stroke of

said part, said part being effective during its return stroke for causing backward movement of the transfer wheel with engagement of a tooth thereof against the said detent member for effecting a relative tangential movement of the detent member without retrograde passage of said latter tooth past the detent member, said detent member being effective upon release of the transfer wheel by said part during the return stroke for effecting a limited return of the transfer wheel in the forward direction.

17. A power take-off structure for an oscillating device and effecting intermittent net forward motion of a driven element, comprising a transfer wheel having teeth and connected to the driven element, means for actuating said transfer wheel and including a part oscillating with said device and effective during the forward and return strokes of said device to move the transfer wheel back and forth, a resilient detent member supported for movement in two directions at angles to one another of a portion thereof contacted and moved successively by the wheel teeth and positioned relative 20 to the path of said teeth so that the wheel has limited freedom of position while it is not being moved from said actuating means but is limited in its movements within said freedom of position so that at least one tooth 25 thereof is always presented for such actuation in either

5

10

direction, said part being effective during one stroke of said device to cause a tooth of the transfer wheel to produce a movement of a contacted part of said detent member in one said direction whereby the transfer wheel advances forwardly past the detent member, and a stop for limiting motion of said detent member in the other said direction during such one stroke of the device, said part being effective during the succeeding stroke of the device for causing a tooth of the transfer wheel to produce a movement of a contacted part of said detent member in the other said direction without retrograde passage of said latter tooth past the detent member, said detent member being effective upon release of the transfer wheel from said part during the return stroke for effecting a limited return of the transfer wheel in the forward direction.
